MEDICINE KIT

Filed Feb. 18, 1927

INVENTOR
CARL BORNMANN
BY *Philip S. Hopkins*
ATTORNEY

UNITED STATES PATENT OFFICE.

CARL BORNMANN, OF BINGHAMTON, NEW YORK, ASSIGNOR, BY MESNE ASSIGNMENTS, TO AGFA ANSCO CORPORATION, OF BINGHAMTON, NEW YORK, A CORPORATION OF NEW YORK.

MEDICINE KIT.

Application filed February 18, 1927. Serial No. 169,387.

The principal objection to most of the medicine kits now in common use lies in the fact that they are bulky and inconvenient in that they usually necessitate the un-
5 buckling of straps, sometimes the removal of trays, packing, etc. and frequently the removal one at a time of the remedies or other articles within the kit, before the particular remedy is made available. This often results in delay which not only is incon-
10 venient but sometimes disastrous.

By my invention, I have provided a neat, compact, portable medicine kit equally adaptable to home or field use and which 15 because of its ready portability and convenience, readily lends itself to the use of campers and vacationists.

In addition to the particular advantages 20 of my improved kit, I have so designed it that it simulates in appearance a folding camera, which design, in addition to lending thereto the faculty of being easily carried, takes away by its appearances that thought of repulsiveness which is invariably 25 associated with the sight of a medicine kit.

An important feature of my invention resides in the construction of a kit which permits a number of medicine bottles or vials 30 to be held firmly in position without danger of rattling or striking one another and wherein they are all visible to the eye immediately upon opening the kit, and from which they may be readily selected.

As an added feature, and as a surety 35 against breakage, I have provided special means as a part of the kit or casing for cushioning the bottles in their proper places within the kit.

Other objects and advantages in details 40 of construction and operation will be apparent as the description proceeds, reference now being had to the figures of the drawing wherein like reference numerals indicate like parts.

In the drawing:—

Figure 1 is a perspective view of my im- 45 proved medicine kit in its opened position.

Figure 2 is a detail cross section of the kit 50 in closed position, illustrating the method of retaining the bottles therein.

As before stated, my medicine kit is de- 55 signed to simulate a folding camera and to this end, I have provided a sectional case

similar in appearance and construction to 55 the body and cover of such a folding camera. The lower section indicated by the reference numeral 1 provides a compartment within which the medicine bottles 2 may be secured, and hinged to one end of this compartment, as at 2^a, is the cover section 3. Both sections 1 and 2 are provided at their sides with the flanges 4 and 5 whereby when the sections are closed as shown in Figure 2, there is ample room within the kit for bot- 60 tles of substantial size. The ends of the sections 1 and 3 are preferably curved as at 6 to further lend to the kit the appearance of a camera.

A handle 7 is secured to one end of the 70 section 3 as by means of the brackets 8. Means are also provided for fastening the sections shut, comprising the pin 9 carried at the free end of the section 3 and the slide- 75 able catch 10 mounted on the corresponding end of section 1.

Secured as by rivets 11 to the bottom of the compartment formed in section 1, are two rows of spring clips 12, preferably 80 staggered with respect to each other and having their upper free ends turned outwardly as at 13 whereby to permit the ready insertion of the bottles 2 therein. These clips 12 may be made of thin spring metal and of such size and form as to embrace 85 and securely hold in position the bottles 2. By staggering the clips as shown in Figure 1, it is possible to dispose of more bottles within the kit than would be feasible otherwise.

Also secured to the bottom of the section 1 as by gluing or otherwise, are strips 14 of 90 velvet, felt, or other soft cushion material. These strips 14 are disposed lengthwise of the section on either side of the rows of clips 12 and the thickness of the material 14 is greater than the thickness of the material from which the clips are made. Therefore, 95 as clearly illustrated in Figure 2, the bottles 2 are supported at either end on these strips of cushion material above the lower portion of the clips 12 and out of contact with both the metal clips and the bottom of the section. It is preferable also that the inner 100 face of the upper section 3 be lined as at 15 with the same cushion material, the same engaging the upper side of the bottles 2 when the cover 3 is closed. The bottles 2

90

100

105

are of course of such a length that with the cap 16 screwed thereon, they fit snugly between the flanges 4 and 5 of the sections.

- From the foregoing construction, it will be observed that I have provided a medicine kit which when opened presents to view the entire contents which may be selected at once and with ease, merely by grasping the bottles and lifting them out of the clips 12.
- 10 When the case is closed and not in use, the bottles are rendered safe from breakage, the collection of dirt, etc., and the kit may be placed in a position for instant use without being unsightly or obnoxious, or may be 15 readily carried in one's pocket if desired.

Of course, many changes may be made by way of detail without departing from the spirit and scope of my invention. I do not limit myself therefore to the exact structure 20 shown and described other than by the appended claims.

I claim:—

- 25 1. A medicine kit comprising hinged sections, clips in one of said sections for receiving medicine receptacles, strips of cushion material in said section on each side of said clips on which said bottles rest, said cushion material being thicker than the material of said clips.
- 30 2. A medicine kit comprising hinged sections, clips secured in one of said sections for receiving medicine receptacles, and cushion means on each side of said clips for supporting said receptacles out of contact

with the bottom of said section and said 35 clips.

3. A medicine kit comprising hinged sections, clips secured to the bottom of one of said sections for embracing the sides of medicine receptacles to hold the same there- 40 in, and cushion means in said receptacle for supporting said receptacles at their ends out of contact with the bottom of said section and said clips.

4. A medicine kit comprising hinged sec- 45 tions, clips secured to the bottom of one of said sections for embracing the sides of medicine receptacles to hold the same there- in, and cushion means in said receptacle for supporting said receptacles at their ends 50 out of contact with the bottom of said sec- tion and said clips, and cushion means in the other of said sections for engaging the upper sides of said receptacles.

5. A medicine kit comprising hinged sec- 55 tions, a plurality of staggered spring clips secured to the bottom of one of said sec- tions, for removably receiving medicine re- 60 ceptacles, strips of cushion material in the bottom of said section on either side of said clips, said strips being thicker than the ma- terial of said clips, whereby said receptacles are supported at their ends above the bot- 65 tom of said clips, and a lining of cushion material in the other of said sections for en- gaging the upper sides of said receptacles.

CARL BORNMANN.
